UNITED STATES PATENT OFFICE.

ABLE G. HEATH, OF NEW YORK, N. Y.

KEROSENE-LAMP.

SPECIFICATION forming part of Letters Patent No. 359,968, dated March 22, 1887.

Application filed May 10, 1886. Serial No. 201,784. (No model.)

To all whom it may concern:

Be it known that I, ABLE GROVE HEATH, of the city, county, and State of New York, have invented certain new and useful Improvements in Kerosene-Lamps without Chimneys; and I do hereby declare that the following is a full, clear, and exact description of the construction and operation of the same.

My invention relates to that class of lamps in which a fan operated by clock-work supplies a constant current of fresh air to the burner, thereby dispensing with a chimney.

The invention consists in the construction and combination of parts hereinafter set forth, and specified in the claims annexed to this specification.

By reference to the drawing forming part of this specification, it will be seen that the figure represents a side sectional view of my improved lamp.

A represents the glass oil-reservoir surrounded with the outer casing, B, leaving an air-space, C, between them.

D is the lower portion of the lamp, which contains the central air-tube, fan, and devices for driving the fan.

E is the central metal tube, preferably of brass tubing, affixed to the sides of the lamp by brackets F.

G is the fan, placed near the top inside portion of the central air-tube, E. It revolves the spindle H, which is carried by the bracket I and center cross-piece, J. The lower part of the said spindle is formed with a worm, and a worm-wheel, K, attached to the horizontal shaft L, is made to engage with it, and so revolve it with the fan. The wheel-movement for driving the fan is placed outside of the said tube E, and inside of the bracket-plate M, which is secured to the said tube E, and, in connection with the wall of the tube E, gives bearing to the spindles L N O P, with their pinions and movement-wheels; but upon which I do not make any claim, as they are the usual clock-movement.

Q is the spring placed on the shaft P, and made to be easily wound up by the key R, on the outside of the lamp, for running the wheel-movement and fan.

S are openings in the base of the lamp to admit air to the central tube, E, and thence through the fan to the spaces C C up to the burner T.

U is a stop device employed to engage the worm on the spindle H, and so, if desired, stop the fan and wheel-movement when the lamp is not burning.

The operation of the lamp may be described as follows: It is first supplied with oil and the wick properly trimmed. The spring Q is then wound up by means of the key R, which sets the wheels in motion to drive the fan G, which, as it revolves rapidly, draws up the air through the central tube, E, from the openings S at the base, and causes a continuous upward current of fresh air through the spaces C, to supply the burner with oxygen without the use of a globe or chimney. The lamp will thus give out a bright white flame without smoke or odor, and also be cool, safe, healthy, and non-explosive; and the movement is calculated to run for about twenty-four hours after each full winding up. It will further be observed that when a round wick and burner are used the central tube, E, will be connected to the burner by means of an additional tube, V, through the oil-reservoir A, as shown by dotted lines.

The upper part of the bracket-plate M covers the clock mechanism sufficiently to prevent any danger of oil, soot, or charred wick falling into the gearing, and thereby clogging its movements.

It will be observed that the lamp is so constructed that all its parts can be readily seen and reached for repairs and cleaning without taking it all to pieces.

Having thus described my device and its advantages, what I claim as my invention, and desire to secure by Letters Patent, is—

1. The combination, with the central air-tube, E, a fan, G, located in said tube, and a clock-work mechanism exterior to the tube for operating said fan, of a bracket-plate, M, having its upper part located above said clock-work mechanism to protect it from oil and soot, substantially as described.

2. The combination, with the central air-tube, E, fan G, located in said tube, the worm-spindle H, supporting said fan, and a clock-work mechanism exterior to the tube and
5 geared with said worm-spindle, of the movable stop U, engaging the worm-spindle, to prevent the rotation of the fan, substantially as described.

Dated at Hamilton, Canada, this 29th day of April, 1886.

A. G. HEATH.

In presence of—
A. E. JONES,
W. BRUCE.
